DRILLING RIG

John E. Renfer, Cleveland, Ohio, assignor to The
Cleveland Rock Drill Company, Cleveland, Ohio,
a corporation of Ohio

Application August 26, 1935, Serial No. 37,821

10 Claims. (Cl. 255—51)

This invention pertains broadly to drilling apparatus, but more particularly to supporting rigs for fluid actuated drills commonly known as wagon drills.

One object of this invention is to produce an improved drilling apparatus of the wagon drill type.

Another object of this invention is to provide a wagon drill with a mechanism whereby the drill may be positioned for drilling holes in different positions relative to the frame supporting the drill, and may be adjusted vertically and longitudinally of the latter.

Another object of this invention is to produce a wagon drill of simple construction, constituting an assembly which is strong, durable and efficient.

Other objects and advantages more or less ancillary to the foregoing reside in the specific construction and aggroupment of the elements peculiar to this structure, as will become apparent from a more complete examination of this specification.

Referring to the drawings which illustrate a preferred embodiment of the invention:

Fig. 1 is a top plan view of the front end portion of a drilling apparatus having the invention applied thereto.

Fig. 2 is a longitudinal sectional view of the complete apparatus taken in a plane indicated by line 2—2 in Fig. 1.

Fig. 3 is a view similar to Fig. 2, illustrating the front end portion of the apparatus with the drilling motor shown in a different position.

Fig. 4 is an enlarged sectional view taken in a plane indicated by line 4—4 in Fig. 2.

Fig. 5 is a cross sectional view taken in a plane indicated by line 5—5 in Fig. 4.

Fig. 6 is a cross sectional view taken in a plane indicated by line 6—6 in Fig. 5.

Fig. 7 is a cross sectional view taken in a plane indicated by line 7—7 in Fig. 4.

Fig. 8 is a cross sectional view taken in a plane indicated by line 8—8 in Fig. 6.

Fig. 9 is an enlarged sectional view taken in a plane indicated by line 9—9 in Fig. 2.

Fig. 10 is a side elevational view of a drilling apparatus having a modified form of the invention applied thereto.

In this illustrative construction, there is shown a carrying frame 15 having wheels 16, 17 and 18 rotatably secured thereto by which the frame is supported. The frame 15 includes two side members 19 and 20 having their rear end portion united by a bracket 21 carrying the wheel 18. The front end portion of the members 19

and 20 are maintained in spaced relations, and thereby constitute the open front end of the frame, the purpose of which will be explained hereinafter. To the inner wall of each of the side members 19 and 20 there is secured by bolts 22 an annular member or track 23, which is located close to the front end of the side member and disposed vertically to extend above and below the same. The peripheral wall 24 of each track 23 is provided with a relatively narrow ridge 25 having teeth 26 cut thereon. This peripheral wall has side walls 27 and 28 extending inwardly therefrom, thus constituting an annular track or guide of substantially U shaped cross section having a bottom wall 29. The bolts 22 extend through the side wall 28 and the corresponding side member of the supporting frame 15 to receive the nuts 30, by which the track is rigidly secured to the frame.

Extending from one to the other track 23, there is a tubular cross member 31 having each end portion thereof formed with a vertical wall 32 depending therefrom. The wall 32 is externally machined to provide two parallel arcuated surfaces 33 and 34, the former slidably engaging the inner portion of the track peripheral wall 24, while the latter is slidably engaging the end of the track side wall 27. On its inner side, the wall 32 is formed with two radially disposed bosses 35, each having a bolt 36 extending therethrough cooperating with a nut 37 and a clamp 38 for locking the cross member 31 against movement relative to the tracks 23. As shown in Fig. 6, the clamp 38 is L shaped and has one end formed with a ridge 39 engaging the bottom of the boss 35, while the other end is arcuated as at 40 in Fig. 8, for engagement with the arcuated bottom wall 29 of the track 23. The wall of the clamp leading from the arcuated end 40 is also in engagement with the side wall 27 of the track 23 to prevent the spreading of the side members 19 and 20 of the carrying frame 15.

Longitudinally disposed through the tubular cross member 31, there is a shaft 41 having each end supported within a bearing 42 formed in a cap 43 secured to each end of the cross member by bolts 44. To each end portion of the shaft 41 is keyed a gear or pinion 45 meshing with the teeth 26 of the corresponding track 23. Intermediate its ends, the cross member 31 is formed with a transversally disposed boss 46, having an aperture 47 extending therethrough and adapted to rotatably accommodate a worm 48. Each end of the aperture 47 is threaded to receive a nut 49 through which extends the reduced corresponding end of the worm, which is 55

shaped as at 50 to accommodate a handle 51 by which the worm may be rotated. The worm 48 is in constant operative engagement with the teeth of a worm gear 52 keyed on the shaft 41.

5 Pivotedly secured to the cross member 31 by a clamp 53, there is an elongated drill guiding frame 54 having a drilling motor 55 slideable thereon. In this illustrative construction, the elongated frame 54 has a feeding mechanism 10 therein operatively associated with the drilling motor for imparting forward or backward feeding movement thereto.

15 Pivotedly secured to the drill guiding frame 54 by a clamp 56, there is one end of a jack 57, which has its other end pivotally connected to the supporting frame 15. By operating the jack 57, pivotal movement is imparted to the drill guiding frame, which may thereby be moved 20 from horizontal to vertical position relative to the carrying frame 15.

25 Referring to the modification shown in Fig. 10, it will be seen that the mechanism shown therein is substantially the same as that previously described. In the former the tracks or guides 58 are of greater diameter than the tracks 23 of the latter, and are located to extend considerably higher above the frame 59, which correspond to the carrying frame 15. On the cross member 60, which is a replica of the cross member 31, is pivotally mounted a clamp 61, which in turn is adapted to receive the center housing 62 of a drill guiding frame 63. This housing is mounted within the clamp 61 in a manner permitting the pivotal movement of the drill guiding frame on an axis normal to the longitudinal center axis of the cross member 60. Since the connection between the cross member 60 and drill guiding frame 63 does not form a part of this invention, and that the construction shown in Fig. 10 is only a modified application of the invention, no further description is 35 thought necessary.

40 In the operation of the mechanism, when the worm 48 is rotated through the crank handle 51, rotation is imparted to the worm gear 52, thus imparting rotation to the pinions 45 through 45 the shaft 41. The pinions 45 engaging the teeth 26 of the circular tracks 23, will cause the tubular cross member 31 to travel on the tracks in a circular path passing between the two side members 19 and 20. Due to the movement of the tubular cross member 31, it will be understood that the drill guiding frame, together with the drill 55 therein, may be elevated or lowered with respect to the carrying frame, and be adjusted longitudinally of the latter. Due to the movement of the cross member 31, and the pivotal connection of the drill guiding frame therewith, the drill 55 may be moved in various drilling positions, above or below the carrying frame, while one end of the drill guiding frame is movable through the open end of the carrying frame.

45 The cross member 31 may be locked against movement relative to the carrying frame in any position possible by virtue of its travel on the arcuated tracks or guides 23, by tightening the nuts 37 cooperating with the bolts 36, for causing the clamping engagement of the arcuated 50 end wall 40 of the clamps 38 with the bottom wall 29 of the tracks 23.

55 Although the foregoing description is necessarily of a detailed character in order to completely set forth the invention, it is to be understood that the specific terminology is not in-

tended to be restrictive or confining, and it is to be further understood that the mechanism herein described may well be used in connection with other types of rock drills or rock drill guiding frames without departing from the scope and 5 spirit of the invention as herein claimed.

I claim:

1. In a portable drilling rig, the combination with a substantially horizontal wheel supported carrying frame, stationary tracks carried by said frame in perpendicular relation therewith, a member carried by said tracks independently of said carrying frame for guided movement on said tracks, a drill detachably secured to said member, said tracks extending longitudinally of said carrying frame and from above to below the latter to enable the adjustment of the drill into various drilling positions longitudinally of said frame above or below the latter due to the movement of said member on said tracks, and means 20 for establishing a rigid connection between said member and frame in any drilling position assumed by said drill by virtue of the movement of said member on said tracks.

2. In a portable drilling rig, the combination 25 of a carrying frame having an open end, supporting wheels carried by said frame, stationary guiding means carried by said frame extending above and below the latter and having traction means formed thereon, an element carried 30 by said guiding means capable of guided movement thereon through the open end of said frame, a drill detachably secured to said element, a mechanism including rotatable means carried by said element operatively engaging said traction means and having rotation imparted thereto for causing the movement of said element and the consequential movement of said drill in various drilling positions relative to said frame, and means for locking said element and drill against 40 movement relative to said frame.

3. In a portable drilling rig, the combination of a carrying frame, a duality of racks carried by said frame, an element carried by said racks for movement relatively thereto, a drill detachably secured to said element, gears carried by 45 said element and meshing with said racks, a mechanism operable for imparting rotation to said gears to cause the movement of said element, said racks formed and disposed in a manner whereby said element upon rotation of said 50 gears is capable of adjustment from above to below said frame and longitudinally of the latter, and means for establishing a rigid connection between said element and frame in any 55 drilling position assumed by said drill by virtue of the adjustment of said element.

4. In a portable drilling rig, the combination of a carrying frame including two side members, a circular member secured to each of said side members and extending above and below the same, an element entirely carried by said circular members, connecting means between said circular members and element affording the latter to rotate around the former, a drill carried 60 by said element, and means for establishing a rigid connection between said element and frame in any drilling position assumed by said drill by virtue of the rotation of said element around 65 said circular members.

5. In a portable drilling rig, the combination of a carrying frame, a duality of spaced circular stationary members mounted on said frame in coaxial alignment with each other, an element entirely carried by said members, connecting means 75

between said members and element affording the movement of the latter around the former, a drilling mechanism carried by said element, one end of said mechanism being movable through 5 the space between said members, and means for locking said element and frame against relative movement.

6. In a portable drilling rig, the combination of a carrying frame including two side members, a 10 stationary gear carried by each of said side members in coaxial alignment with each other, an element extending from one to the other of said gears, pinions carried by said element meshing with said gear, a mechanism operable for imparting rotation to said pinions for moving of said element in a circular path, a drill carried by said element, and means for establishing a rigid connection 15 between said element and frame in any drilling position assumed by said drill by virtue 20 of the movement of said element.

7. In a portable drilling rig, the combination of a substantially horizontal wheel supported carrying frame, arcuated racks on said frame, a drill guiding frame, a connecting mechanism between 25 said frames entirely carried by said racks and including gears meshing with said racks for adjustably moving said drill guiding frame relative to said carrying frame, and means for locking said frames against relative movement.

30 8. In a portable drilling rig, the combination of a substantially horizontal carrying frame, arcuated supporting wheels for said frame, track stationary on said frame, a drill guiding frame, a connecting mechanism between said frames entirely carried by said tracks and including operable means co-operating with traction means

formed on said tracks for adjustably moving said drill guiding frame relative to said carrying frame, and means for locking said frames against relative movement.

9. In a portable drilling rig, the combination of 5 a substantially horizontal carrying frame, supporting wheels for said frame, stationary arcuated guiding means on said frame having traction means formed thereon, an element carried by said guiding means for guided movement thereon, a 10 drill guiding frame detachably secured to said element, a mechanism including means co-operating with said traction means for effecting the movement of said drill guiding frame in various operative positions relative to said carrying frame, 15 and means for locking said frames against relative movement.

10. In a portable drilling rig, the combination of a carrying frame, supporting wheels for said frame guiding means on said frame having traction means formed thereon, an element carried by said guiding means for guided movement thereon, a drill detachably secured to said element, means carried by said element cooperating with said traction means for effecting the movement of said 25 element, said guiding means extending longitudinally of said frame from above to below the latter whereby said element due to the movement thereof on said guiding means is adjustable longitudinally of said frame and from above to below 30 the latter, and means for establishing a rigid connection between said element and frame in any drilling position assumed by said drill by virtue of the adjustment of said element.

35 JOHN E. RENFER.
